US00D551488S

(12) **United States Design Patent** (10) Patent No.: **US D551,488 S**
Ting et al. (45) Date of Patent: **** Sep. 25, 2007**

(54) TOASTER	2,785,547 A	3/1957	Barros
(75) Inventors: LuJie Ting , Shenzhen (CN); Brian K. Beesley , Draper, UT (US)	D183,177 S	7/1958	Oertli
	2,851,258 A	9/1958	Siehrs
	D186,419 S	10/1959	Keefe
	2,945,634 A	7/1960	Beck et al.
(73) Assignee: Back to Basics Products, Inc. , Bluffdale, UT (US)	D189,904 S	3/1961	Seltsam
	3,013,775 A	12/1961	Bruntjen
	D194,389 S	1/1963	Bejamin
	3,088,345 A	5/1963	Campbell
	3,104,089 A	9/1963	Seltsam
	3,107,711 A	10/1963	Azmus
(21) Appl. No.: 29/260,915	D199,888 S	12/1964	Dewenter
(22) Filed: Jun. 1, 2006	D200,230 S	2/1965	Seltsam
(51) LOC (8) Cl. 07-02	D205,827 S	9/1966	Plagenberg
(52) U.S. Cl. D7/330	3,315,947 A	4/1967	Nauta
(58) Field of Classification Search D7/323, D7/328-333, 385, 390, 340, 341, 346, 365, D7/367, 402, 405, 406, 407, 411; D13/158, D13/162, 162.1, 163; D21/525; 99/331, 332, 99/357, 375, 385; 219/214, 388, 405, 443.1, 219/450.1, 492	3,346,029 A	10/1967	Harris
	3,355,068 A	11/1967	Harland
	3,396,655 A	8/1968	Yoshida et al.
	3,417,972 A	12/1968	Vincent
	3,427,636 A	2/1969	Seifert
	3,765,275 A	10/1973	Johnson
	3,780,393 A	12/1973	Gaetke
	3,895,548 A	7/1975	Sauve
	3,920,224 A	11/1975	Fassauer
	3,938,784 A	2/1976	Moreton
	4,030,707 A	6/1977	Moreton
	4,071,789 A	1/1978	Ernster et al.
	D249,701 S	9/1978	Maples et al.
	4,116,366 A	9/1978	Takenakashima et al.
	4,119,020 A	10/1978	Sharp et al.
	4,137,578 A	2/1979	Felici
	4,201,487 A	5/1980	Backhaus
	4,250,771 A	2/1981	Berler
	4,252,160 A	2/1981	Numbers
	4,268,080 A	5/1981	Lindley
	4,337,000 A	6/1982	Lehmann
	4,357,861 A	11/1982	Di Girolamo
	D267,841 S	2/1983	Leslie
	D268,811 S	5/1983	Adams
	D269,471 S	6/1983	Auerbach
	4,395,792 A	8/1983	Cosner
	4,397,427 A	8/1983	Howard
	D271,368 S	11/1983	Belland et al.
	4,488,664 A	12/1984	Cleland
	4,501,538 A	2/1985	Bray et al.
	4,513,688 A	4/1985	Fassauer
	4,537,332 A	8/1985	Brown et al.
	4,561,782 A	12/1985	Jacobsen et al.
	D295,138 S	4/1988	Hyde

(57) CLAIM

The ornamental design for a toaster, as shown and described.

DESCRIPTION

FIG. 1 is a front, left perspective view of the toaster in accordance with our invention;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in FIGS. 1-7 are for illustrative purposes only and form no part of the claimed design.

1 Claim, 4 Drawing Sheets
